(57) **CLAIM**

The ornamental design for a video game storage device, as shown and described.

DESCRIPTION

FIG. 1 is a perspective view of the video game storage device according to the present invention.

FIG. 2 is a front view of the video game storage device of FIG. 1.

FIG. 3 is a rear view of the video game storage device of FIG. 1.

FIG. 4 is a right side view of the video game storage device of FIG. 1.

FIG. 5 is a left side view of the video game storage device of FIG. 1.

FIG. 6 is a top view of the video game storage device of FIG. 1; and,

FIG. 7 is a bottom view of the video game storage device of FIG. 1.
